(57) CLAIM

The ornamental design for a leaf-gathering rake having an ergonomically contoured telescopically adjustable handle, as shown and described.

DESCRIPTION

FIG. 1 is a top perspective view of a leaf-gathering rake having an ergonomically contoured telescopically adjustable handle, showing my new design;

FIG. 2 is a top plan view thereof;

FIG. 3 is a bottom view thereof;

FIG. 4 is a right side view;

FIG. 5 is a left side view;

FIG. 6 is an upper end view taken from the right of FIG. 4; and,

FIG. 7 is a lower end view taken from the left of FIG. 4.
